A. A. BOWERMAN,

TWISTING MACHINE FOR YARNS, COTTONS, AND THE LIKE.

APPLICATION FILED NOV. 24, 1920.

1,386,233.

Patented Aug. 2, 1921.

FIG. 1

UNITED STATES PATENT OFFICE.

ALLEN ARTHUR BOWERMAN, OF HOPE BAY, BRITISH COLUMBIA, CANADA.

TWISTING-MACHINE FOR YARNS, COTTONS, AND THE LIKE.

1,386,233.

Specification of Letters Patent.

Patented Aug. 2, 1921.

Application filed November 24, 1920. Serial No. 426,191.

To all whom it may concern:

Be it known that I, ALLEN ARTHUR BOWERMAN, a subject of the King of Great Britain, and a resident of Hope Bay, in the 5 Province of British Columbia, Canada, have invented certain new and useful Improvements in Twisting-Machines for Yarns, Cottons, and the like, of which the following is a specification.

10 My invention relates to improvements in machines for twisting yarn, cotton, silks and the like; or for making the same into spools, and the object of my invention is to devise a machine capable of accomplishing this 15 object in a simple, practical, and highly satisfactory manner.

I attain this object by the construction illustrated in the accompanying drawings in which—

20 Figure 1 is a side elevation of the machine.

Fig. 2 is a front end view.

Fig. 3 is a rear end view.

25 Fig. 4 is a detail view in perspective of the "cylinder."

Fig. 5 is a detail view of the roller driving mechanism.

Similar figures of reference indicate similar parts throughout the several views.

30 1 indicates generally the front end frame of the machine consisting of the side uprights 2 and 3 connected together by upper and lower transverse members 4 and 5 respectively, while 6 indicates generally the 35 rear end frame consisting of the side uprights 7 and 8 connected together by the upper and lower transverse members 9 and 10, the upper transverse member 9 being provided with a plurality of spaced vertical

40 pins 11, as shown in Fig. 3, on which are rotatably mounted bobbins 12 filled with the material to be twisted, a guide plate 13 for the threads being mounted on the frame in advance of the bobbins having separate 45 notches 14 for each thread to run in, as shown in Fig. 3. 15 indicates a roller mounted on the frame 1 for supporting the threads at the front end of the machine.

Rotatably mounted between the front 50 transverse members 4 and 5 is what may be termed the "cylinder" of the machine, indicated generally by the numeral 16, consisting of upper and lower circular plates 17 and 18 connected together by bars 19, 20, 55 and 21, the upper plate being provided with a central tubular journal 22 extending ro-

tatably through the member 4 while the lower plate is rotatably mounted on a shaft 23 which extends at its opposite ends through the plate 18 and lower transverse member 5, being rotatable in a bearing 24 fitted into the member 5, bevel gears 25 and 26 being secured to the opposite ends of the shaft, as shown more particularly in Fig. 5. A sheave 27 is secured centrally to the underside of the plate 18 and through the sheave the shaft 23 also passes freely.

28 indicates a shaft rotatably mounted on the cylinder 16 provided with a bevel gear 29 meshing with the gear 25 and having 70 toward one end a spur pinion 30 meshing with a spur gear 31 secured to one end of a roller 32, this roller being rotatably mounted on a shaft 33 one end of which is secured to the bar 19 of the cylinder. A similar 75 roller 34 is mounted rotatably adjacent the upper end of the cylinder on a shaft 35 also secured at one end to the bar 19, as shown more particularly in Fig. 2. At suitable points on the bar 19 between the rollers 32 80 and 34 arms 36 and 37 are pivotally connected so as to be capable of being swung to and remaining in any adjusted position, each of which arms carries at one end a guide roller, 38 and 39 respectively. 40 indicates the main driving shaft, operated by any suitable means, which shaft is mounted transversely of the machine at the rear thereof and is provided with a cone gear 41 belt-connected to a corresponding cone gear 42 secured to the shaft 43 rotatably mounted on the front end of the machine, this shaft 43 being provided with a bevel gear 44 meshing with the bevel gear 26 on the shaft 23, while 45 indicates a sheave secured to 95 shaft 40 connected by a rope 46 to the sheave 27 on the lower plate 18, as shown in Fig. 1.

The manner in which the machine operates may be briefly described as follows. The respective threads from the bobbins are 100 taken and carried forwardly over the roller 15, being then gathered together at their free ends and passed down through the tubular journal 22, around the lower roller 32, and up over the roller 34, the free ends 105 being then tied to the downwardly extending threads above the roller 34 so that a loop is formed around the rollers 32 and 34, and the loop is so arranged with reference to the guide rollers 38 and 39 that these rollers 110 engage respectively the opposite sides of the loop, that is to say, the loop lies between

the guide rollers and thus the sides of the loop are prevented from flying outwardly as it is rotated. If the machine be now started in operation the cylinder will be 5 rotated by means of the rope 46 while the lower roller 32 will also be rotated by the gear mechanism disposed between it and the shaft 43, as hereinbefore described, so that the threads are unwound from the bobbins 10 and formed into a skein by the rotation of the roller 32 and at the same time the twisting is effected by the rotating cylinder. It will of course be understood that the number of threads and the amount of twist in the 15 finished skein may be readily determined and controlled by the respective speeds at which the roller and the cylinder are driven.

From the foregoing it will be seen that I have devised a simple and inexpensive twisting 20 machine for yarns and the like which is highly practical and efficient.

What I claim as my invention is:—

1. A twisting machine comprising a frame, a cylindrical member mounted vertically on 25 the front end of said frame, said member consisting of an upper circular disk having a central tubular journal and a lower circular disk having a central aperture and a sheave on its underside concentric with the 30 aperture and through which it extends, said disks being connected together by spaced vertical bars, spaced upper and lower rollers rotatably mounted on one of said bars, the lower roller being provided at one end with 35 a gear, a suitably supported driving shaft, a driving connection between said shaft and said gear, and means for supporting a plurality of filled bobbins so that the free ends of the respective threads therefrom may be 40 gathered together and passed through the said tubular journal and looped around said horizontal rollers.

2. A twisting machine comprising a frame, a cylindrical member mounted vertically on 45 the front end of said frame, said member consisting of an upper circular disk having a central tubular journal and a lower circular disk having a central aperture and a sheave on its underside concentric with the 50 aperture and through which it extends, said disks being connected together by spaced vertical bars, spaced upper and lower rollers rotatably mounted on one said bars, the lower roller being provided at one end with 55 a gear, a rotatable shaft carried by said cylinder having a gear at one end meshing with the roller gear and a bevel gear intermediate its length, a shaft extending ver-

tically through the said central aperture 60 having a bevel gear at its upper end meshing with the aforesaid bevel gear and a bevel gear on its lower end, an intermediate shaft rotatably mounted on the frame having a gear meshing with the lower bevel gear of the vertical shaft, a main driving shaft, a 65 driving connection between the main shaft and intermediate shaft, a driving connection between the main shaft and the said sheave, and means for supporting a plurality of 70 filled bobbins so that the free ends of the respective threads therefrom may be gathered together and passed through the said tubular journal and looped around the said horizontal rollers.

3. A twisting machine comprising in combination, a plurality of stationary spool supports, a rotatable frame having a single aperture through which the several strands from the spools associated with said supports are adapted to be passed into the 80 frame, a plurality of rotatable rollers disposed to rotate about an axis at right angles to the axis of rotation of said frame, and means for rotating said frame and one of 85 said rollers.

4. A method of twisting together a plurality of strands and winding the twisted strands into a skein, which consists in passing the several strands through a relatively small opening in a stationary member, then forming the ends of the strands into a loop extending over a pair of spaced rollers disposed with their longitudinal axes at right angles to that of the opening, rotating said 90 rollers about an axis coincident with that of the opening and simultaneously rotating one of said rollers about the longitudinal axes thereof.

5. A twisting machine comprising a frame, a cylinder rotatably supported at its ends 100 by said frame and equipped at one of said ends with a central opening through which the strands to be twisted are introduced into the frame, a pair of spaced rotatable rollers within the cylinder extending transversely 105 thereof, the ends of the said strands being adapted to be passed over the said rollers and secured to form a single loop embracing both of the rollers, and means for simultaneously rotating said cylinder and one of the rollers to twist the strands together and to form the twisted strands into a skein.

Dated at Vancouver, B. C., this 11th day of November, 1920.

ALLEN ARTHUR BOWERMAN.
